UNITED STATES PATENT OFFICE.

CHARLES D. SHAIN, OF ROCKAWAY PARK, NEW YORK.

VAPORIZER OR CARBURETER.

No. 835,564.

Specification of Letters Patent.

Patented Nov. 13, 1906.

Application filed December 26, 1905. Serial No. 293,426.

To all whom it may concern:

Be it known that I, CHARLES D. SHAIN, a citizen of the United States, and a resident of Rockaway Park, in the county of Queens 5 and State of New York, have invented a certain new and useful Vaporizer or Carbureter for Gas-Engines, of which the following is a specification.

My invention relates to improvements in vaporizers or carbureters in which shutters as a throttle are used for regulating the quantity and quality of gas passing into the cylinder of the engine; and the objects of my improvement are, first, to provide regulating shutters as a throttle; second, to afford facilities for furnishing a supply of auxiliary air in proportion to the opening of the shutter-throttle; third, to regulate to a certain extent by means of the shutter-throttle the lift of the automatically-operated air-intake shutters at the bottom of the air-chamber of the vaporizer or carbureter. I attain these objects by the mechanism illustrated in the accompanying drawings, in which—

Figure 1 is a vertical section of the vaporizer or carbureter. Fig. 2 is a top view of the vaporizer or carbureter with the cover of the float-cup removed and the vaporizing-chamber removed at Z. Fig. 3 is a section 30 from X to X, Fig. 2, arranged so as to more fully show the construction. Fig. 4 is a vertical section through a continuation of the line X X, Fig. 2, looking to the left. The arrows at the bottom show the air-inlets and the arrow at the top the gas-outlet to engine.

Similar letters refer to similar parts throughout the drawings.

In Fig. 1 V is a float-cup for gasolene containing a float T, with ball-valve near the 40 top; of the usual construction. The gasolene enters the cup V at the point M and leaves at the points R R and passes through the pipe Y to the tube D, the flow of gasolene being controlled by the ball-valve A, seated 45 in the support B. The adjustment of the ball-valve A is regulated by the thumb-nut I, in conjunction with sliding rods E and a ring H. (See Fig. 4.)

J and J' are two semicircular shutters in 50 the air-chamber K, one hinged on each side of the bottom piece G and raised or lowered automatically by the suction of the engine through the gas-outlet C. (See Fig. 4.)

N and N' are two portions of a hollow 55 sphere forming the shutter-throttle for controlling the amount and quality of the gas

sucked by the engine. They open in opposite directions, as shown by the arrows, and are arranged on a common axis and operated by and in conjunction with the lever P, gear L, crank g, gear Q, tension-spring h, and the stops f and f'.

a a are a number of auxiliary air-ports located so that the shutter-throttle N and N' uncovers them fully when both N and N' are 65 fully open. The air-ports a a are covered or closed partly or fully when N and N' are partly or fully closed.

The two halves of the vaporizer or carbureter are bolted together at Z'. (See Fig. 4.)

In Fig. 2 b b' is the shaft, and g the crank, of the shutter-throttle N. The shaft b b' is seated to one-half its diameter in each side of each of the two halves of the carbureter, which are bolted together at Z'. (See Fig. 4.) The shaft b' has a tension-spring at h. At the lower end of the lever P is rigidly attached to it a gear L, with a rigid shaft d, (see Fig. 3,) which passes through the crank g of the shutter-throttle N. The shaft b b' is 80 a hollow one, through which passes the shaft c c', which is attached to the shutter-throttle N' at e and e'. (See Figs. 2 and 3.) One end of the shaft c is firmly attached to the gear Q, (see Figs. 1 and 3,) which meshes 85 with the gear L. The movement of the lever P in the direction of the arrow, Fig. 1, in connection with the gear L and the tension-spring h, Fig. 2, turns the gear Q, which in turn moves the shutter-throttle N' until it 90 strikes the stop f. (See Fig. 1.) In this position the shutter-throttle N' would be fully open and shutter-throttle N fully closed. The shutter-throttle N now covers the air-shutter J and intervenes between it and the 95 suction of the engine through C. Therefore J is not raised by the suction of the engine to the same extent it would be if the shutter-throttle N was not covering it. A still further movement of the lever P in the direction of the arrow turns the crank g, which moves the shutter-throttle N until the bottom strikes the stop f'. (See Fig. 1.) The 100 throttle N and N' would then be completely open.

When it is desired to shut off a portion of the supply of gas to the engine, the lever P is turned in the opposite direction to the arrow, which moves the gear Q, turning the shutter-throttle N' to its full closed position, 110 if desired. In this fully-closed position the shutter-throttle N' will be directly interven-

ing between the suction of the engine through C (see Fig. 1) and the air-shutter J'. Therefore the air-shutter J' is not raised by the suction from the engine to the same extent it would be if the shutter-throttle N' was not covering it.

This vaporizer or carbureter can be made in several ways; but I prefer to carry out this feature of my invention as shown in the drawings.

The arrangement of a float-cup V, with a float T, in connection with a vaporizer or carbureter forms no part of my invention.

What I do claim as my invention, and desire to secure by Letters Patent, is—

1. In a vaporizer or carbureter, a shutter-throttle made of two portions of a hollow sphere; each of these portions turning in opposite directions on a common axis by means of gears, a crank, a lever, a tension-spring and stops arranged so that each portion may at times be moved separately, all substantially as set forth.

2. In a vaporizer or carbureter, a shutter-throttle made of two portions of a hollow sphere; each of these portions turning in opposite directions on a common axis by means of gears, a crank, a lever, a tension-spring and stops arranged so that each portion may

30 at times be moved separately and air-ports near the top of the mixing-chamber arranged so that they may be closed, partly uncovered and fully uncovered by the closing, par-

tial opening and opening of the shutter-throttle, all substantially as set forth.

3. The combination in a vaporizer or carbureter of a shutter-throttle made of two pieces of a hollow sphere; each of these portions turning in opposite directions on a common axis by means of gears, a crank, a lever, a tension-spring and stops arranged so that each portion may at times be moved separately and air-ports near the top of the mixing-chamber, arranged so that they may be closed, partly uncovered and fully uncovered by the closing, partial opening and opening of the shutter-throttle, with hinged air-shutters at the bottom of the air-chamber of the vaporizer or carbureter, the raising or lowering of which may be controlled in a measure by the intervention of a part of the shutter-throttle between the gas-outlet and the air-intake shutters at the bottom of the air-chamber, and a ball seated in a support and a tube for gasoline or liquid fuel discharging under the ball; the adjustment of the ball regulated by a thumb-nut in conjunction with sliding rods and a ring, all substantially as set forth.

Witness my hand this 22d day of December, 1905, at the city of New York, in the county and State of New York.
